METHOD OF PRESERVING PACKAGED MATERIALS

John M. Ellis, Lafayette, Calif.

Application February 10, 1950, Serial No. 143,527

12 Claims. (Cl. 226—68)

This invention relates to a process of preserving oxidizable materials and to a composition and apparatus for carrying out the process.

In preserving liquids and semi-liquid, or plastic materials such as paints from the harmful effects of oxidation, a known method consists in evacuating the container, or introducing an inert gas under pressure into the head space of the container. These methods are effective and are suitable for a manufacturer, but they have a serious limitation in that, when the evacuated or pressurized vessel is opened, the protective vacuum or inert gas is lost. More often than not, a can of paint or other oxidizable material is not immediately consumed but is only partly consumed and is put away to be used again. Meanwhile the protective vacuum or inert gas has been lost, air has gained access to the material and during the period of storage, oxidation and deterioration occur.

Methods such as pressurizing and evacuating are not suitable for use by the average consumer to obviate this difficulty. Pressurizing with an inert gas requires the use of a material such as solid carbon dioxide which is difficult to store and handle, or the use of a cylinder, a valve and other fittings if a pressurized gas is employed. Also the problem of sealing the container after pressurizing is difficult for the ordinary consumer.

Evacuation is even less suited for use by the average consumer. Expensive evacuation equipment and fittings are required and the problem of sealing an evacuated container is difficult.

It is an object of the present invention to provide a method of preserving oxidizable materials such as paints, which is adapted to use by the average consumer, and which requires no special skill and no expensive equipment.

It is a further object of the present invention to provide a method of preserving oxidizable materials such as paints, which utilizes an inert gas yet avoids the necessity of high pressures and of pressurizing equipment and which solves the problem of sealing the container after a protective atmosphere of inert gas has been created.

It is yet another object of the present invention to provide a simple apparatus, and also an inexpensive chemical composition, which can be employed by the average consumer without special skill or equipment, to create and maintain a protective atmosphere of inert gas in the head space of a partly used container of oxidizable material.

These and other objects of the invention will be apparent from the ensuing description and the appended claims.

In accordance with my invention, an inert gas which is heavier than air, preferably carbon dioxide, is formed in situ in the head space of a can or other vessel containing the oxidizable material which is to be preserved. This is preferably accomplished in the following manner:

A boat of suitable size relative to the size of the container and the available head space, is provided. This boat may be of simple construction, preferably embodying the features of construction described hereinafter, and

it is preferably of light construction so as to float on the surface of the paint or whatever material is to be preserved. It will also be constructed of a material which is inert to the material to be preserved. Preferably it is constructed of aluminum foil and is sufficiently shallow and/or is provided with gas deflecting features as described hereinafter, so that a heavy gas generated in the boat, will immediately sink to the surface of the liquid to be preserved. Alternatively, instead of a boat intended to float on the surface of the paint, any suitable vessel may be provided and attached to the lid, lip or wall of the can.

Carbon dioxide, being odorless, non-toxic and inert as well as heavier than air, is the preferred gas. It is generated chemically in situ preferably in the manner described hereinafter, at atmospheric pressure or at a low super-atmospheric pressure. It is generated in the boat while floating on the surface of the liquid content of the container, which meanwhile has its lid removed or resting loosely on the container. As the gas is generated it will sink to the level of the liquid and will gradually rise in the head space of the container, displacing air therefrom until the head space is completely filled with the inert gas and is completely devoid of air. The lid of the container will then be replaced and firmly engaged with the container. If desired, a sealing compound may be applied, but with a suitable, press-fitting lid of the type employed on paint cans, or a screw lid provided with a sealing gasket, this is unnecessary. The seal provided by the usual closure of either type will, in conjunction with the specific gravity of the protective gas, cut down diffusion of the protective gas to a point of insignificance over a long period of time.

In an alternative embodiment of my invention, which may be carried out with the same apparatus, instead of generating an inert gas a material may be placed in the boat which absorbs oxygen from the air in the head space.

Suitable apparatus for carrying out the method of the invention is illustrated in the accompanying drawings, in which

Figure 1 is a vertical sectional view, more or less diagrammatic, of a can of paint or the like and the dispensing boat and composition of the invention, showing the same at the start of operations.

Figure 2 is a similar view showing the can and boat at the conclusion of operations.

Figure 3 is a view similar to that shown in Figure 1, with the vessel containing the operative material suspended within the container from the lip thereof.

Figure 4 is a view similar to that of Figure 2 with the vessel containing the operative material suspended from the lid and within the container.

Referring now to these drawings, a can 10 is illustrated having a press-fitting lid 11 and it is shown partly filled with a liquid material 12, such as paint, which is oxidizable. A shallow boat 13 is provided which may be constructed of heavy aluminum foil or light gauge sheet aluminum. This boat is notched at its rim, as shown at 14, and it is provided with a cap 15 having a downwardly and outwardly slanting annular flange or rim 16. The cap 15 is seated on the notched rim, as shown. A gas generating composition 17 is placed in the boat 13 to generate a heavy, inert gas, such as carbon dioxide at a relatively low pressure. This gas will be deflected outwardly and downwardly as indicated by the arrows, and it will gradually rise in the head space 18 to displace air therefrom.

It will be seen in Figure 1 that, during this displacement, the lid 11 rests loosely on the can 10. Alternatively, the lid may be removed completely from the can, but I prefer to leave it resting loosely on the can.

Completion of the air displacement may be sensed in

various ways. If the heavy, inert gas has a characteristic odor or color, either per se or as an impurity, such will be noted when displacement is complete. In the case of carbon dioxide, and provided of course that the liquid 12 is non-inflammable, a lighted match held close to the mouth of the can will be extinguished by the carbon dioxide on completion of the displacement.

In any event, an accurate gauging of the displacement is not critical provided any error lies on the side of "over" displacement; i. e., provided more than sufficient inert gas is generated. This may be insured, and will automatically insure complete displacement, by proportioning the chemical reagents in the manner described herein-after, so as to generate a predetermined and sufficient amount of inert gas.

In Figure 2 a complete blanket of protective inert gas 25 is shown and the lid 11 is closed and sealed. It will be seen that the boat 13 is left in the closed, sealed can. This may be safely done provided the can is to be left stationary and right side up. Otherwise, it should be fished out at the conclusion of the displacement operation, as by hand or with a pair of tongs.

If the boat is left in the can, it is advisable to allow the chemical reaction to go to completion before closing the lid, or to calculate the quantities of reagents relative to the available head space; otherwise, continuation of this chemical reaction may occur and an unduly high pressure may develop in the can after it is closed.

As shown in Figure 3, the vessel is an envelope 13a of impervious material, having a front portion 27 and a rear portion 26, containing the operative mixture 17 and sealed at all four edges. The vessel is placed in operating condition by tearing off the top edge thereof, peeling down the front edge 29 to expose the contents, and folding back the rear edge 28 so that it engages and hooks over the inner upper rim of the container 10. In this manner the edge 28 will be retained between the can rim and the lid 11 without destroying the seal of the container. It makes no difference whether or not the lower portion of the container 13a extends into the liquid 12 or not, so long as the opening is above the liquid level.

In Figure 4 the vessel 13 has serrated openings 14 with outwardly extending tabs 14a, having pressure sensitive adhesive 19 thereon for instantaneous engagement and holding with the interior of the can lid 11, as shown.

In generating the inert gas, I may use any of a variety of materials. Preferably, however, I employ pelleted solids capable of forming carbon dioxide when treated with a small amount of water. Thus, in one of the preferred embodiments of the invention, I provide dry acidic pellets of citric acid or oxalic acid and dry basic pellets of sodium bicarbonate or other solid material capable of yielding carbon dioxide when mixed with the acid pellets and a small amount of water. More generally stated, in this embodiment of the invention I provide a pellet or pellets capable of yielding carbon dioxide on treatment with water or with water and a mild acid, and in those cases where an acid reagent is needed I also provide an acid pellet of mildly acid nature sufficient to liberate carbon dioxide from the basic pellets.

These pellets, both basic and acid, may be formed from the pure reagents, or each reagent may be mixed with an inert diluent. And in another embodiment of the invention the reagents may be pre-mixed and formed into pellets, with or without a diluent. The mixed pellets will not react to produce carbon dioxide as long as they remain dry but do so react when they are moistened with water.

Typical chemical reactions involved are as follows:

(1)

These equations omit the water of crystallization normally present in crystals of citric and oxalic acids, and, of course, as is known, the presence of added water is required for the reactions to occur at normal temperatures.

Stoichiometric calculations will show, assuming pellets of pure reagents, that in Equation 1 approximately 7 grams of pellets (in the proper stoichiometric proportions) will yield 1 liter of CO_2 (S. T. P.). In Equation 2, about 6.5 grams of pellets will yield 1 liter of CO_2 . In the reaction represented by Equation 2, a 0.75 gram pellet of oxalic acid dihydrate and a 1 gram pellet of anhydrous sodium bicarbonate will yield $\frac{1}{2}$ pint of CO_2 . Pellets of this size provide a convenient unit for household use. Thus, if it is estimated that a partly used paint can has one quart of head space, four each of these pellets will be employed to yield approximately the correct volume of CO_2 at normal temperature and atmospheric pressure.

It will be apparent that similar calculations can be readily made for other pellets, taking into account water of crystallization, purity and the amount (if any) of diluent.

It will also be apparent that a complete kit can readily be provided for use by the house holder, comprising a boat as described above, a supply of pellets in a suitable container or containers and a set of instructions including a scale for estimating the number of pellets to be used.

The instructions will also indicate how much water to use to bring about the reaction. In this connection it is necessary to use only a few drops of water when only a few pellets, of the order of 10, more or less, are used. No precise control over the amount of added water need be exercised, and adding it drop by drop in accordance with predetermined instructions will suffice. These instructions can be arrived at empirically without any difficulty. At the conclusion of the reaction the pressure can be equalized by leaving the lid of the container open to allow escape of excess gas, or if need be more pellets and water may be added to generate more gas.

It will be apparent that other means than solid pellets may be used to generate the heavy gas. Thus a liquid reactant such as vinegar or dilute acetic acid may be reacted with a solid bicarbonate, or a charged liquid such as carbonated water may be used. Thus a small bomb of the latter may be placed in the boat and punctured to liberate carbon dioxide slowly. However, solid pellets are preferred.

As stated hereinabove, instead of generating an inert gas such as carbon dioxide, a material may be placed in the boat which absorbs oxygen from the air in the head space. To this end a chemical absorbent or a physical adsorbent for oxygen may be used. In employing a chemical absorbent such as pyrogallic acid or sodium sulfite, the general procedure described above may be used. The absorbent material may be pelleted and the pellets may be provided of a convenient size. Thus, pellets may be employed of a size calculated to absorb all of the oxygen in, say, $\frac{1}{2}$ pint of air at normal atmospheric temperature and at standard pressure. The user will, as in the case of CO_2 generating pellets, estimate the volume of head space and will employ a moderate excess of the unit pellets, calculated to absorb all the oxygen in the head space.

By the term "absorb" as used in the appended claims it is intended to include both absorption and adsorption phenomena unless otherwise expressly qualified.

It will thus be apparent that a method is provided for protecting an oxidizable liquid or other material such as paints, and that a simple kit and paraphernalia are provided for executing this method. The method and the kit are simple and they lend themselves to use by the average consumer, such as a householder, who wishes to protect paint in a partly used container to prevent skin formation

thereon. The method and kit are applicable, of course, to other oxidizable materials, such as fruit juices, coffee, etc. Difficulties inherent in the usual pressurizing and evacuating methods are obviated.

I claim.

1. A method of preserving the unused portion of oxidizable materials and the like, comprising providing a resealable container partly filled with said material leaning head space above the surface thereof in said container, suspending a container within said head space, providing said container with dry reagents including a mixture of citric acid and sodium bicarbonate, adding water to said reagents to generate carbon dioxide in situ in the head space above the material, and then closing the container.

2. A method of preserving the unused portion of oxidizable materials and the like, comprising providing a resealable container partly filled with said material, suspending a vessel within and from the lip of said container, providing dry reagents including oxalic acid and sodium oxalate for said vessel, adding water to said reagents to generate carbon dioxide in situ in the head space above the material in such manner as to fill the head space from the surface of the material upwardly, continuing said generation until the air therein has been substantially completely displaced, and then closing the container.

3. A method of preserving the remainder of partially used oxidizable materials and the like, comprising providing a resealable container partly filled with such material, suspending a vessel within and from the lip of said container, placing in said vessel solid reagents capable of reacting to generate a heavy gas when moistened, adding water to initiate the generation of heavy gas allowing reaction to occur until the air in the head space has been displaced, and then closing the container.

4. A method of preserving the unused portion of oxidizable materials and the like, comprising providing a resealable container partly filled with such material, suspending a vessel within and from the lip of said container, placing in said vessel solid reagents capable of reacting to generate carbon dioxide when moistened, adding moisture to initiate the reaction, allowing reaction to occur until the air in the head space has been displaced, and then closing the container.

5. A method of preserving the remainder of oxidizable materials and the like, comprising providing a resealable container partly filled with such material, suspending a vessel within and from the lip of said container, placing in said vessel reagents capable of reacting when moistened to generate carbon dioxide, moistening said reagents to generate carbon dioxide, allowing said reaction to occur until the air in the head space has been displaced, and then closing the container with said vessel therein.

6. A method of preserving the unused portion of oxidizable materials and the like, comprising providing a releasable container partly filled with such material, placing a boat on the surface thereof, placing in said boat a mixture containing an alkali metal bicarbonate and a solid acidic substance capable of reacting with the bicarbonate to liberate carbon dioxide, moistening said acidic substance and bicarbonate to liberate carbon dioxide, allowing said reaction to occur until the air in the head space has been displaced, and then closing the container.

7. The method of preserving the remainder of partially used oxidizable materials comprising providing a resealable container partly filled with such material, placing a boat therein on the surface of the material, placing in the boat pellets of solid reagents capable of reacting to

produce a heavy gas when moistened, adding water in quantity sufficient to initiate reaction and liberate sufficient heavy gas to displace the air in the head space above the material, allowing reaction to proceed until such displacement occurs, and then closing the container.

8. The method of preserving the remaining portion of oxidizable materials comprising providing a resealable container partly filled with such material, placing a boat therein on the surface of the material, placing in the boat 10 pellets of sodium bicarbonate and pellets of a solid acid capable of reacting with the bicarbonate, when moistened, to liberate carbon dioxide, adding water in quantity sufficient to initiate reaction and liberate sufficient carbon dioxide to displace the air in the head space above the material, allowing reaction to proceed until such displacement occurs, and then closing the container.

9. A method of preserving the remainder of partially used oxidizable materials and the like, comprising unsealing a container of such material originally packaged in sealed condition and having a resealing closure, removing a portion of said material from said container leaving it 20 partially filled, introducing into the head space of said container above the material a substance which is operable to remove the oxygen therein, and then resealing the container.

10. A method of preserving the remainder of partially used oxidizable materials and the like, comprising unsealing a container of such material packaged in sealed condition and with a resealing closure, dispensing a portion 30 of said material leaving the container partially filled, placing a vessel within the head space of the container and above the material, containing chemicals capable of producing a heavy inert gas by the addition of another chemical, adding the required chemical for the reaction, generating a heavy inert gas in situ in the head space above the material and then resealing the container.

11. A method of preserving partially used oxidizable materials and the like comprising unsealing a container of such material having a press-fitting lid which is supplied in sealed condition, dispensing a portion of said material, introducing into the head space of the container above the remaining portion of the material a substance which is operable to absorb the oxygen therein, and then resealing the container.

12. A method of preserving the unused portion of oxidizable materials and the like comprising unsealing a container of such material originally supplied in sealed condition with a resealing closure, dispensing a portion of said material leaving the container partially filled, introducing into the head space of the container above the remaining material a chemical absorber for oxygen in a quantity sufficient to absorb the oxygen in said head space, and then resealing the container.
